UNITED STATES PATENT OFFICE.

WARREN B. FLANDERS, OF PITTSBURGH, PENNSYLVANIA, ASSIGNOR, BY MESNE ASSIGNMENTS, TO THE COLONIAL TRUST COMPANY, TRUSTEE, OF PITTSBURGH, PENNSYLVANIA, A CORPORATION OF PENNSYLVANIA.

TURBINE-BLADE.

1,050,119.

Specification of Letters Patent. Patented Jan. 14, 1913.

Application filed February 7, 1911. Serial No. 607,176.

To all whom it may concern:

Be it known that I, WARREN B. FLANDERS, a citizen of the United States, and a resident of Pittsburgh, in the county of Allegheny and State of Pennsylvania, have made a new and useful Invention in Turbine-Blades, of which the following is a specification.

This invention relates to means for securing blades or vanes to a blade holding element.

As an example of the application of the invention I have illustrated blades for Parsons's type turbine secured to a base strip by suitable fastening devices.

In the drawings: Figure 1 is a fragmental perspective view of a base strip to which a plurality of blades are attached; Fig. 2 is a plan view of the base strip, the blades being shown in section; Fig. 3 is a section on the line 3—3 of Fig. 2; and Fig. 4 is a detail perspective view of one of the inserts or fastening devices for securing the blades and base strip together.

A preferred embodiment of my invention is illustrated in the drawings as comprising a base strip 5 having a straight side 6 and an incline side 7; the incline side being adapted to fit in an undercut portion in a groove in the element which is adapted to receive it. The strip 5 is illustrated as being provided with a plurality of approximately comma-shaped openings 8, which extend laterally through the strip 5 and which are adapted to receive the ends of blades 9. The contours of the blades are concavo-convex, that is, the convex face 10 of each blade 9 will be of approximately the same shape as the edge 11 of the opening 8 which receives it. The thickness of each blade 9 is less than the width of the opening 8 so that the space between the concave portion 12 of each blade and the edge 13 of the opening 8 may be filled by an insert or filler piece 14. The filler piece or insert 14 is best shown in Fig. 4 as being approximately

comma-shaped in cross section. The blades and inserts may be introduced into the openings 8 of the base strip and the inserts swaged or calked into the sockets or openings 8 so as to upset them; that is, change the cross sectional area of the insert and thereby securely fasten the roots of the blades 9 in the base strip. 50

Units comprising a base strip, blades and inserts or packing pieces may be made of any desired lengths ready to be inserted into the turbine element to receive them. The preferred form of base strip will be that shown in Fig. 1 so that the base strips may 60 be put in grooves and fastened in by wedges in a manner commonly employed at this time; however, it is obvious that the particular form of base strip shown is not essential to my invention. 65

Having thus described my invention what I claim and desire to secure by Letters Patent is:

1. The combination of a base strip having approximately comma-shaped openings, 70 blades in the openings and inserts filling the spaces between the faces of the blades and edges of the openings.

2. The combination with a base strip having a plurality of openings therein, blades 75 fitting in the openings and packing pieces for securing the roots of the blades in the openings in the strip, the packing pieces being of approximately the same cross-sectional area as the spaces which are to receive them. 80

3. The combination with a base strip having comma shaped openings, blades in the openings and having their convexed faces conforming to one side of an opening in the strip, and a packing piece interposed in the opening between a concave face of the blade and one edge of the opening. 85

4. A base strip having a plurality of openings, a blade for each opening and having 90 its convex side bearing against one edge of the opening, a space being formed between

the convex side of the blade and the opening, and a packing piece insertible in said space to fasten the blade in its opening, the packing pieces being of approximately the same cross-sectional area as the spaces which are to receive them.

In testimony whereof, I have hereunto

subscribed my name this 3rd day of February, 1911.

WARREN B. FLANDERS.
